UNITED STATES PATENT OFFICE.

DAVID F. VAUGHAN, OF HADDONFIELD, NEW JERSEY.

ANTICREEPER FOR RAILROAD-RAILS.

1,021,388.

Specification of Letters Patent.

Patented Mar. 26, 1912.

Application filed August 11, 1911. Serial No. 643,508.

To all whom it may concern:

Be it known that I, DAVID F. VAUGHAN, a citizen of the United States, residing at Haddonfield, in the county of Camden and State of New Jersey, have invented certain new and useful Improvements in Anticreepers for Railroad-Rails, of which the following is a specification.

This invention relates to anticreepers for railroad rails.

The object of the invention is to provide a novel anticreeper which will effectually prevent the creeping of rails, which may be readily applied to or removed from rails, which is provided with parts pressed into gripping position upon the rail by a spring part or member in tending to assume a position from which it was sprung, and which will increase its gripping action with any tendency of the rail to creep.

The invention consists in the provision of a spring part and a pair of jaws, the spring part exerting pressure in a direction lengthwise of the rail and pressing said jaws toward each other and into engagement with the rail base, or the spring part pressing said jaws down upon the top of the rail base, or both, to effect the gripping action.

The invention consists further in constructing the parts so that any tendency of the rail to creep will assist the spring in forcing the jaws toward each other and cause the anticreeper to increase its grip upon the rail.

The invention consists further, in arranging the spring to lock the jaws, or two members on which the jaws are formed, together, in addition to pressing the jaws into engagement with the rail base.

The invention consists further in arranging the spring to exert a pressure in one direction lengthwise of the rail against a part engaging a stationary part of the road bed and to exert a pressure in the reverse direction against two rail gripping jaws and force them into engagement with the rail; and the invention consists further in various novel features of construction and combinations of parts hereinafter fully described and particularly claimed.

In the accompanying drawings, illustrating my invention: Figure 1 is a side eleva-

tion of a portion of a cross tie and a railroad rail thereon, provided with my improved anticreeper. Fig. 2 is a vertical section, on line 2—2 of Fig. 1. Fig. 3 is a bottom view of the parts shown in Fig. 1. Fig. 4 is a section through the lower portion of a railroad rail showing positions of parts of the anticreeper while being applied thereto. Fig. 5 is a section through one of the clamping members, on line 5—5 of Fig. 4. Fig. 6 is a view of the spring, detached. Fig. 7 is a bottom view of a portion of a railroad rail, and cross tie showing a modified form of the anticreeper applied to the rail. Fig. 8 is a view of the spring, detached, for the modification shown in Fig. 7. Fig. 9 is a section through one of the clamping members on the same line that the section shown in Fig. 5 is taken, showing a modification of the spring engaging surfaces.

3 designates a portion of a railroad cross tie and 4 a railroad rail of well known construction including the base 6. The cross tie forms a stationary part of the road bed which supports the rail 4 and over which the rail tends to creep under the well known conditions.

My improved anticreeper is applied to the rail base 6 adjacent the cross tie 3 and is of the following construction: Arranged beneath the rail 4 are two members 7 and 8, the outer ends of which are provided with jaws 9 and 10, respectively, which embrace and extend over the edges of the rail base 6. The inner ends of the members 7 and 8 are provided with off-set portions 11 and 12 which overlap each other, as shown, permitting the tops of the main bodies of the members 7 and 8 to be substantially in the same horizontal plane and permitting the bottom portions of the members 7 and 8 to extend below the off-set portions 11 and 12. The off-set, inner end 11 of the member 7 is provided with a downwardly-extending pivot pin 13 which extends through and is fitted to an opening in the off-set inner end 12 of the member 8, pivoting the members 7 and 8 together and permitting them to move about the vertical axis of the pin 13 in a manner to move the jaws 9 and 10 toward each other and in a direction substan-

tially lengthwise of the rail 4 and into engagement with the edges of the rail base 6.

When herein I speak of forwardly, I mean in the direction of the arrows, shown 5 in the drawings, or in the direction from the anticreeper to the cross tie, and when herein I speak of rearwardly, I mean in the reverse direction.

Extending rearwardly from the lower portions of the members 7 and 8 are flanges 14 and 15, respectively, the upper faces of which are inclined to converge downwardly, as shown; and the rearward faces 16 and 17 of the members 7 and 8, above the flanges 15 14 and 15, respectively, are inclined to converge forwardly, as shown, for a purpose presently explained.

The lower end of the pivot pin 13 is provided with a reduced portion 18 which extends below the overlapping ends of the members 7 and 8. The reduced portion 18 is provided with a perforation through which extends a spring pin or key 19 which also extends transversely of the rail 4, and 25 is engaged with the tops of the flanges 14 and 15 and with the faces 16 and 17 of the members 7 and 8. This pin is normally straight, as shown in Fig. 6, when removed from the other parts of the anticreeper. 30 When, however, the parts are assembled, as shown in Figs. 1, 2 and 3, the central portion of the pin 19 presses upwardly and rearwardly upon the pivot pin 13 or the bottom of the inner portion of the member 8, or 35 both, the end portions of the pin 19 press forwardly against the faces 16 and 17 of the members 7 and 8, and the end portions of the pin 19 press downwardly upon the flanges 14 and 15.

40 The rearward pressure of the pin 19 against the pivot 13 and the forward pressure of the ends of the pin 19 against the faces 16 and 17 forces the central portions of the members 7 and 8 rearwardly and 45 forces the jaws 9 and 10 on the outer ends of the members 7 and 8 forwardly and into gripping position against the edges of the rail base 6; and the upward pressure of the pin 19 against the central, overlapping portions of the members 7 and 8, and the downward pressure of the ends of the pin 19 against the flanges 14 and 15 forces said overlapping portions up against the bottom of the rail 4, and forces the jaws 9 and 10 55 down upon the top of the rail base 6, holding said members together and the jaws thereof down upon the rail base.

The inner portion of the member 8 is provided with a forwardly-extending part 59 or abutment 20, the forward face of which is arranged adjacent and is adapted to abut against the cross tie 3.

When the parts are assembled, as shown in Figs. 1, 2 and 3, and as hereinbefore described, the outer ends of the members 7 and

8 and the jaws 9 and 10 are maintained in spaced relation to the cross tie 3 by the part 20. Should the rail 4 attempt to creep forwardly or in the direction of the arrows, over the cross tie 3, the forward movement 70 of the part 20 and the pivoted inner ends of the members 7 and 8 will be prevented by the engagement of the part 20 with the cross tie 3, and the rail, in creeping forwardly, will carry the jaws 9 and 10 with it; and immediately, upon the initial creeping movement of the rail 4, the jaws 9 and 10 will tend to move toward each other thereby firmly gripping the rail and preventing creeping thereof, and increasing the gripping action 80 of the jaws upon the rail with the increasing pressure tending to cause the rail to creep.

In assembling the parts of the anticreeper and applying the anticreeper to the rail, 85 the jaw 9 is first hooked over one edge of the rail base 6 and the body of the member 7 is moved up against the bottom of the rail 4, in the position shown in Fig. 4. The jaw 10 is then hooked over the other edge 90 of the rail base 6 and the member 8 is moved up into engagement with the member 7 and the bottom of the rail 4, the pivot pin 13 entering the opening in the member 8 during the upward movement of the member. 95 This being done, the pointed end of the spring pin 19 is inserted into the perforation in the extension 18 of the pivot pin, the body of the pin 19 is placed over either the flange 14 or the flange 15 and the pin 19 is 100 driven through the perforation and over the other flange until about the central portion of the pin 19 reaches the pivot pin 13. As the pin 19 is driven in, it assumes the curved form shown in Figs. 1 and 3 and exerts 105 the pressure upon the parts of the anticreeper, hereinbefore described.

The spring pin may be driven into place from either side of the rail, and when in place, as shown in Figs. 1, 2 and 3, the pin 110 is prevented from accidentally moving out of place through the perforation in the part 18 by stops 21 and 22 projecting rearwardly from the outer ends of the inclined faces 16 and 17, respectively, the stops 21 and 22 having beveled faces and projecting sufficiently to prevent accidental longitudinal displacement of the pin 19, in either direction, but not far enough to prevent the pin 19 from being driven against the beveled faces, into or out of place, in either direction, in applying the anticreeper to or removing it from the rail.

In lieu of providing the two inclined surfaces 14 and 16, for the member 7 and the two inclined surfaces 15 and 17 for the member 8, I may employ a single inclined pin-engaging surface for each member, which single surfaces will incline downwardly and rearwardly and will converge forwardly, 130

thus causing the ends of the spring 19 to exert forward and downward pressure against the members 7 and 8. In Fig. 9, I have illustrated a transverse section 5 through the member 8 showing at 23 one of the single inclined surfaces.

In the modification shown in Fig. 7, the construction is the same as that shown in Figs. 1, 2 and 3, except as follows: In lieu 10 of the inclined rearward faces 16 and 17, the members 7 and 8 are provided with rearward faces 24 and 25 which extend substantially parallel to the members, and no flanges 14 and 15 are provided, and in lieu 15 of the round spring pin 19, a flat or square spring pin 26 is provided which extends through a similarly shaped perforation in the extension 18 of the pivot pin 13 to prevent turning of the spring 26. The spring 20 26 is normally curved, as shown in Fig. 8, and when driven into place, as shown in Fig. 7, the pin 26 is straightened to some degree causing its ends to press against the surfaces 24 and 25 and press the outer ends 25 of the members 7 and 8 forwardly and the jaws thereof into gripping position against the rail while the central portion of the spring pin 26 exerts a rearward pressure against the pivot 13. In this modification 30 the spring 26 does not exert any upward or downward pressure against the members 7 and 8.

In anticreepers it is desirable that the parts shall be constructed and related to each other so that any tendency of the rail to creep will force the parts firmly against the rail to grip the same; it is also desirable that the parts of the anticreeper be pressed into gripping engagement with the rail by 35 a spring part so that the anticreeper will be in constant readiness for action under all conditions and so that the anticreeper may not work loose or shift its position upon the rail due to expansion and contraction of 40 the rail and the parts of the anticreeper and due to the jarring of the rail by the passage of car wheels thereover. To accomplish the latter desirable characteristic I have provided the spring acting in the novel manner 45 to force the clamping jaws toward each other and against the rail by a pressure exerted in a direction lengthwise of the rail and in the direction against which it is desired to prevent the rail from creeping, or 50 acting in the novel manner to press the jaws down upon the top of the rail base while pressing a part of the anticreeper up against the bottom of the rail or both. These are 55 the essential features which characterize my invention and to these I broadly lay claim; and, in this broad aspect of the invention the specific means for connecting the jaws together is capable of wide variation without departing from my invention.

60 I claim:

1. The combination with a railroad rail and a stationary part of a road bed, of an anticreeper comprising jaws engaging the sides of the rail, and means for forcing said jaws toward each other and against the rail, 70 said means including a spring exerting pressure in a direction longitudinally of the rail, said anticreeper having a part engaging said stationary part.

2. The combination with a railroad rail 75 and a stationary part of a road bed, of an anticreeper comprising jaws engaging the sides of the rail, means for forcing said jaws toward each other and against the rail, said means including a spring exerting pressure in a direction longitudinally of the rail, 80 and a part engaging said stationary part and connected to the anticreeper beneath a position between the sides of the rail.

3. The combination with a railroad rail 85 and a stationary part of a road bed, of an anticreeper comprising two members having parts engaged with each other, a jaw on one member engaging one side of the rail, a jaw on the other member engaging the other side of the rail, and a spring pressing 90 said members into engagement with each other and pressing said jaws against said rail, one of said members having a part 95 engaging said stationary part.

4. The combination with a railroad rail and a stationary part of a road bed, of an anticreeper comprising two separable members having spring-engaging parts, a jaw on one member engaging one side of the rail, a 100 jaw on the other member engaging the other side of the rail, and a spring engaging said spring-engaging parts and forcing said jaws against the rail, one of said members having a part 105 engaging said stationary part.

5. The combination with a railroad rail and a stationary part of a road bed, of an anticreeper comprising two separable members having spring-engaging parts, a jaw on one member engaging one side of the rail, a jaw on the other member engaging the other side of the rail, and a spring exerting 110 pressure against one of said members in two directions opposite to each other and exerting pressure against the other of said members in one direction and forcing said jaws against the rail, one of said members having a part 115 engaging said stationary part.

6. The combination with a railroad rail 120 and a stationary part of a road bed, of an anticreeper comprising two separable members having parts preventing separation of said members when engaged with each other, a jaw on one member engaging one side of the rail, a jaw on the other member engaging the other side of the rail, one of said members having a part 125 engaging said stationary part, and a spring exerting pressure against one of said members in two directions opposite to each other and exerting 130

pressure against the other of said members in one direction and forcing said jaws against the rail.

7. The combination with a railroad rail and a stationary part of a road bed, of an anticreeper comprising two separable members having parts preventing separation of said members when engaged with each other, a jaw on one member engaging one side of the rail, a jaw on the other member engaging the other side of the rail, and a spring locking said members together and forcing said jaws against the rail, one of said members having a part engaging said stationary part.

8. The combination with a railroad rail and a stationary part of a road bed, of an anticreeper comprising jaws engaging the sides of the rail, means extending beneath the rail and connecting said jaws and forcing said jaws toward each other and against the rail, said means including a spring forcing said jaws in one direction lengthwise of the rail and forcing a part of said connecting means in the reverse direction, said anticreeper having a part engaging said stationary part and causing the tendency of the rail to creep to increase the pressure of the jaws against the rail.

9. The combination with a railroad rail having a base, and a stationary part of a road bed, of an anticreeper comprising two members extending beneath the rail base and having parts engaged with each other, one of said members having a part engaging said stationary part, a jaw on one member engaging one edge of the rail base, a jaw on the other member engaging the other edge of the rail base, and a spring pressing one of said members up against the bottom of the rail base and pressing said jaws down upon the top of the rail base.

10. The combination with a railroad rail having a base, and a stationary part of a road bed, of an anticreeper comprising two members pivoted together beneath the rail base, one of said members having a part engaging said stationary part, a jaw on one member engaging one edge of the rail base, a jaw on the other member engaging the other edge of the rail base, and a spring pressing one of said members up against the bottom of the rail base and pressing said jaws down upon the top of the rail base.

11. The combination with a railroad rail and a stationary part of a road bed, of an anticreeper comprising two members pivoted together beneath the rail, a jaw on one member engaging one side of the rail, a jaw on the other member engaging the other side of the rail, one of said members having a part engaging said stationary part, and a spring pressing said jaws against the rail.

12. The combination with a railroad rail

and a stationary part of a road bed, of an anticreeper comprising two members pivoted together beneath the rail permitting the outer portions thereof to move on said pivot in the direction in which it is desired to prevent the rail from creeping, a jaw on one member engaging one side of the rail, a jaw on the other member engaging the other side of the rail, a spring forcing said jaws in said direction and against the rail, and a part engaging said stationary part and connected to the anticreeper beneath a position between the sides of the rail.

13. The combination with a railroad rail and a stationary part of a road bed, of an anticreeper comprising two members pivoted together beneath the rail, a jaw on one member engaging one side of the rail, a jaw on the other member engaging the other side of the rail, one of said members having a part engaging said stationary part, and a spring exerting pressure in one direction against one of said members and in a reverse direction against both of said members and pressing said jaws against said rail.

14. The combination with a railroad rail and a stationary part of a road bed, of an anticreeper comprising two members pivoted together beneath the rail permitting the outer portions thereof to move on said pivot in the direction in which it is desired to prevent the rail from creeping, a jaw on one member engaging one side of the rail, a jaw on the other member engaging the other side of the rail, a spring exerting pressure in said direction against both of said members and pressing said jaws against the rail and exerting pressure in a reverse direction against one of said members, and a part engaging said stationary part and connected to the anticreeper beneath a position between the sides of the rail.

15. The combination with a railroad rail and a stationary part of a road bed, of an anticreeper comprising two members having parts engaged with each other, a jaw on one member engaging one side of the rail, a jaw on the other member engaging the other side of the rail, one of said members having a part engaging said stationary part, and a spring exerting pressure in one direction pressing said members into engagement with each other and exerting pressure in a reverse direction pressing said jaws against said rail.

16. The combination with a railroad rail and a stationary part of a road bed, of an anticreeper comprising two members having parts engaged with each other, a jaw on one member engaging one side of the rail, a jaw on the other member engaging the other side of the rail, a spring exerting pressure in one direction against both said members and pressing the jaws against the rail.

and exerting pressure in a reverse direction against one of said members, and a part engaging said stationary part and connected to the anticreeper beneath a position between the sides of the rail.

17. The combination with a railroad rail having a base, and a stationary part of a road bed, of an anticreeper comprising two members pivoted together beneath the rail
10 base, one of said members having a part engaging said stationary part, a jaw on one member engaging one edge of the rail base, a jaw on the other member engaging the other edge of the rail base, and a spring
15 pressing said jaws toward each other and into engagement with the edges of the rail base, said spring also pressing said jaws down upon the top of the rail base.

18. The combination with a railroad rail
20 having a base, and a stationary part of a
road bed, of an anticreeper comprising two
members pivoted together beneath the rail
permitting the outer portions thereof to move
on said pivot in the direction in which it
25 is desired to prevent the rail from creeping,
one of said members having a part beneath
a position between the edges of the rail base
and engaged with said stationary part, a
jaw on one member engaging one edge of the
30 rail base, a jaw on the other member engag-
ing the other edge of the rail base, and a
spring forcing said jaws in said direction
and against the rail, said spring also press-
ing said jaws down upon the top of the rail
35 base.

19. The combination with a railroad rail having a base, and a stationary part of a road bed, of an anticreeper comprising two members pivoted together beneath the rail
40 base, one of said members having a part engaging said stationary part, a jaw on one member engaging one edge of the rail base, a jaw on the other member engaging the other edge of the rail base, and a spring exerting pressure in one direction against one
45 of said members and in a reverse direction against both of said members and pressing said jaws against said rail, said spring also
50 pressing said jaws down upon the top of the rail base.

20. The combination with a railroad rail having a base, and a stationary part of a road bed, of an anticreeper comprising two members pivoted together beneath the rail 55 permitting the outer portions thereof to move on said pivot in the direction in which it is desired to prevent the rail from creeping, one of said members having a part beneath a position between the edges of the rail base and engaged with said stationary part, a jaw on one member engaging one edge of the rail base, a jaw on the other member engaging the other edge of the rail base, a 60 spring exerting pressure in said direction against both said members and pressing said

jaws against the rail and exerting pressure in a reverse direction against one of said members, said spring also pressing said jaw down upon the top of the rail base.

21. The combination with a railroad rail and a stationary part of a road bed, of an anticreeper comprising a member having an opening therein, a member having a pin extending through and beyond said opening pivotally connecting said members together, one of said members having a part engaging said stationary part, a jaw on one member engaging one side of the rail, a jaw on the other member engaging the other side of the rail, and a spring extending through said pin and locking said members together and pressing said jaws against said rail. 75 80

22. The combination with a railroad rail and a stationary part of a road bed, of an anticreeper comprising a member having an opening therein, a member having a pin extending through and beyond said opening and pivotally connecting said members together permitting the outer portions thereof to move on said pivot in the direction in which it is desired to prevent the rail from creeping, one of said members having a part beneath a position between the edges of the rail base and engaged with said stationary part, a jaw on one member engaging one side of the rail, a jaw on the other member engaging the other side of the rail, and a spring extending through said pin and locking said members together and pressing said jaws in said direction and against said rail. 100

23. The combination with a railroad rail and a stationary part of a road bed, of an anticreeper comprising a member having an opening therein, a member having a pin extending through and beyond said opening pivotally connecting said members together, one of said members having a part engaging said stationary part, a jaw on one member engaging one side of the rail, a jaw on the other member engaging the other side of the rail, and a spring extending through said pin and locking said members together, said spring exerting pressure in one direction against said pin and exerting pressure in a reverse direction against both said members and pressing said jaws against said rail.

24. The combination with a railroad rail and a stationary part of a road bed, of an anticreeper comprising a member having an opening therein, a member having a pin extending through and beyond said opening and pivotally connecting said members together permitting the outer portions thereof to move on said pivot in the direction in which it is desired to prevent the rail from creeping, one of said members having a part beneath a position between the edges of the rail base and engaged with said stationary part, a jaw on one member engaging one side of the rail, a jaw on the other member

- engaging the other side of the rail, and a spring extending through said pin and locking said members together, said spring exerting pressure against said members in said 5 direction pressing said jaws against the rail and exerting pressure in a reverse direction against said pin.
25. The combination with a railroad rail having a base, and a stationary part of a 10 road bed, of an anticreeper comprising a member having an opening therein, a member having a pin extending through and beyond said opening pivotally connecting said members together, one of said members having a part engaging said stationary part, a jaw on one member engaging one edge of the rail base, a jaw on the other member engaging the other edge of the rail base, and a spring extending through said pin and locking said members together and pressing said jaws against said rail, said spring also presssing said jaws down upon the top of the rail base.
26. The combination with a railroad rail having a base, and a stationary part of a 15 road bed, of an anticreeper comprising a member having an opening therein, a member having a pin extending through and beyond said opening and pivotally connecting said members together permitting the outer portions thereof to move on said pivot in the direction in which it is desired to prevent the rail from creeping, one of said members having a part beneath a position between the edges of the rail base and engaged with said stationary part, a jaw on one member engaging one edge of the rail base, a jaw on the other member engaging the other edge of the rail base, and a spring extending through said pin and locking said 20 members together, said spring exerting pressure against said members in said direction pressing said jaws against the rail and exerting pressure in a reverse direction against said pin, and said spring also pressing said 25 jaws down upon the top of the rail base.
27. The combination with a railroad rail having a base, and a stationary part of a 30 road bed, of an anticreeper comprising a member having an opening therein, a member having a pin extending through and beyond said opening and pivotally connecting said members together permitting the outer portions thereof to move on said pivot in the direction in which it is desired to prevent the rail from creeping, one of said members having a part beneath a position between the edges of the rail base and engaged with said stationary part, a jaw on one member engaging one edge of the rail base, a jaw on the other member engaging the other edge of the rail base, and a spring extending through said pin and locking said 35 members together and pressing said jaws in said direction and against said rail, said spring also pressing said jaws down upon the top of the rail base.
28. The combination with a railroad rail having a base, and a stationary part of a 40 road bed, of an anticreeper comprising a member having an opening therein, a member having a pin extending through and beyond said opening pivotally connecting said members together permitting the outer portions thereof to move on said pivot in the direction in which it is desired to prevent the rail from creeping, one of said members having a part beneath a position between the edges of the rail base and engaged with said stationary part, a jaw on one member engaging one edge of the rail base, a jaw on the other member engaging the other edge of the rail base, and a spring extending through said pin and locking said 45 members together, said spring exerting pressure against said members in said direction pressing said jaws against the rail and exerting pressure in a reverse direction against said pin, and said spring also pressing said 50 jaws down upon the top of the rail base.
29. The combination with a railroad rail and a stationary part of a road bed, of an anticreeper comprising jaws engaged with the sides of the rail, means for connecting said jaws together, a spring having its sides engaged with parts of the anticreeper and forcing a part against the rail, and a stop adjacent one end of the spring preventing accidental longitudinal displacement thereof, said anticreeper having a part engaging said 55 stationary part.
30. The combination with a railroad rail and a stationary part of a road bed, of an anticreeper comprising jaws engaged with the sides of the rail, means for connecting said jaws together, a spring having its sides engaged with parts of the anticreeper and forcing a part against the rail, and a stop having a beveled face adjacent one end of the spring preventing accidental longitudinal displacement of the spring and permitting the spring to be removed by force, said anticreeper having a part engaging said 60 stationary part.
- In testimony whereof I affix my signature in presence of two witnesses.
